UNITED STATES PATENT OFFICE.

ELMER B. STONE, OF NEW BRITAIN, CONNECTICUT.

DESIGN FOR A KEY.

42,094.

Specification for Design.

Patented Jan. 9, 1912.

Application filed July 21, 1911. Serial No. 639,856. Term of patent 14 years.

To all whom it may concern:

Be it known that I, ELMER B. STONE, a citizen of the United States, and residing at New Britain, in the county of Hartford and State of Connecticut, have invented a new, original, and ornamental Design for Keys, of which the following is a specification, reference being had to the accompanying drawings, forming part thereof, in which—

The figure is a plan view of a key showing my new design.

A special and distinguishing feature of my design consists in the bow or thumb piece 6 of the key formed on the arc of a circle at its end, and also being of circular form at the opposite sides below said curved end part, the curve of the sides being substantially the same radius as that of the end part and with oppositely curved parts from each of said sides of much larger radius than that

of the side parts that gradually taper the bow from the opposite side parts to the barrel of the key. A bead 7 of substantially circular form in cross-section extends along the entire edge of the bow, this bead gradually decreases in size in diameter from the widest portion at the ends of the bow to the narrowest portion at the longitudinal center, this giving to the bead a concaved appearance. That part of the bow located within the bead is also of concave shape being thinnest at the longitudinal center and thickest at the ends.

I claim—

The ornamental design for a key as shown and described.

ELMER B. STONE.
